Specification for Design.

Patented Oct. 17, 1916.

Application filed September 8, 1916. Serial No. 119,131. Term of patent 3½ years.

To all whom it may concern:

Be it known that I, ANTONINO SICARI, a former subject of the King of Italy, but intending to become a citizen of the United States of America, having had my first naturalization papers issued to me by the Supreme Court of the State of New York on the 18th of February, 1914, and a resident of 152 Lawn avenue, Corona Heights, borough and county of Queens, New York city, New York, whose post-office address is the same, have invented a new, original, and ornamental Design for Textile Fabrics, of

which the following is a specification, reference being had to the accompanying drawing, forming part thereof.

The drawing illustrates a portion of the fabric showing my new design.

I claim:

The ornamental design for a textile fabric, as shown.

ANTONINO SICARI.
